[57] CLAIM

The ornamental design for a shelf, as shown and described.

DESCRIPTION

FIG. 1 is a top plan view of a shelf showing our new design;

FIG. 2 is a right side elevational view thereof, the left side elevational view being identical thereto;

FIG. 3 is a front elevational view thereof, the rear elevational view being identical thereto;

FIG. 4 is an enlarged fragmentary cross-sectional view taken on line 4—4 in FIG. 1; and,

FIG. 5 is a bottom plan view thereof.

Fig. 1.

Fig. 2.

Fig. 4.

Fig. 3.
